UNITED STATES PATENT OFFICE.

JOHN J. MCERLAIN, OF SOUTH BEND, INDIANA, ASSIGNOR OF ONE-HALF TO
FRANK A. BAKER, OF SAME PLACE.

BAND-PULLEY.

SPECIFICATION forming part of Letters Patent No. 394,712, dated December 18, 1888.

Application filed March 22, 1888. Serial No. 268,106. (No model.)

To all whom it may concern:

Be it known that I, JOHN J. MCERLAIN, of South Bend, in the county of St. Joseph and State of Indiana, have invented certain new and useful Improvements in Band-Pulleys; and I do hereby declare that the following is a full, clear, and exact description thereof, reference being had to the accompanying drawings, and to the letters of reference 10 marked thereon, which form part of this specification, in which—

Figure 1 is a face view of my improved split pulley. Fig. 2 is a cross-sectional view of the same. Figs. 3 and 4 are detail views 15 of the sectional hub.

The present invention is an improved split pulley, and its objects are to so construct the same that it can be readily and accurately secured on a shaft; and it consists in the novel 20 and useful construction of the sectional hub and arrangement of parts, as will be herein-after described, and clearly stated in the claims.

Referring to the drawings by letters A A 25 represent the similar but opposite halves of the pulley-hub, which are constructed alike. Sections A have the cylindrical portions B B, which inclose the shaft, and C C are out-standing flanges projecting centrally from 30 parts B. The portions B are formed on arcs of a circle having the axis of the shaft upon which the pulley is mounted as its center, and the portions B are provided at their edges above and below flanges C with radial 35 perforated lugs E E, through which pass the bolts e e, for securing the portions of the hub on the shaft. The end edges of flanges C C, however, are not formed on lines radiating from the axis of the shaft, but on lines 40 projecting tangentially from its periphery at opposite sides, as shown. It will thus be seen that while the parts B of the hubs are separated diametrically the flanges C C are not, but are divided on lines tangential to the 45 parts B. On the inner faces of flanges C are formed the peripheral angular lugs c c, and in the countersinks f f between these lugs are secured the inner ends of spokes G G.

50 In the drawings I have illustrated but three

lugs c and three spokes on each flange C, and to the outer ends of these spokes are secured in suitable manner the sections H II of the pulley-rib. Owing to the peculiar construction of the flanges C, the spokes G G do 55 not radiate from the axis of the pulley, but tangentially thereto and to each other, as shown. When the sections of pulleys are bolted together, as shown, upon a shaft, no direct longitudinal strain is given to any spoke, 60 so that should the ends of the rim-sections meet before the parts B are properly bound to the shaft the spokes will yield laterally sufficiently to enable the hub-sections to be properly bolted together. While the parting- 65 line of the rim-sections is diametrical to the axis of the pulley, still it is tangential to the parting-line of the hub-sections.

I represent rods passing through adjoining spokes G of the opposite rim-sections and 70 provided with suitable washers and nuts, i, by which the rods can be tensioned to draw the ends of the rim-sections together. Owing to the fact that only lateral strain can be exerted on the spokes G in securing the pulley 75 in place, the hub-sections or the rim-sections can be tightened to compensate for slight errors in length of the sections and make close joints throughout.

The hub-sections B have on their inner 80 faces a series of longitudinal grooves, b b, as shown, for the reception of bushing-blocks J J, of wood or other suitable material. By varying the thickness of these blocks the pulley can be fitted to varying sizes of shafts. The 85 blocks J may be fitted, inserted, and secured in place in the hub-sections before the pulley is sent out of the shop to insure the true mounting of the pulley on its shaft.

K K are metal plates corresponding in contour to flanges C C and bolted to the latter above the ends of spokes G, the bolts passing through said spokes to secure the same in place.

Having described my invention, I claim— 95

1. In a split pulley, the combination, of the opposite diametrically-parted hub-sections having projecting flanges and the rim-sections, with the spokes secured to said flanges and rim-sections tangentially thereto, and the 100

securing and uniting bolts and nuts for said hub and rim sections, all constructed and arranged substantially as described.

2. In a split pulley, the combination of two opposite sections, each composed of a flanged hub-section, spokes secured to the flanges of the hub portions tangentially thereto, and the diametrically-opposite lugs on said portions, with the rim-sections, the securing bolts for the hub portions, and the rods and nuts secured to the spokes for closing the joints of the rim-sections, substantially as described.

3. The combination of the hub-sections, flanges C thereon, having lugs c, with the tangential spokes G and plates K, rim-sections, and rods I, all constructed and arranged substantially in the manner and for the purpose described.

20 4. The combination of the hub-sections, the projecting flanges thereon having countersinks in their inner faces, the spokes secured tangentially to said flanges, the rim-sections on said spokes, with the plates K K, rods I I,

and nuts i, substantially as and for the purpose described.

5. The combination of the hub-sections provided with the flanges C thereon, having peripheral lugs c and the grooves b in the inner faces of said sections, with the blocks J, 30 spokes G, plates K, rods I, and rim-sections II, all constructed and arranged substantially in the manner and for the purpose specified.

6. The combination of the opposite pulley-sections having hub-sections A A, formed with semi-cylindrical portions B B, having longitudinal grooves b b in their inner faces, with the series of bushing-blocks J, fitted into said grooves, and the uniting bolts and rods, all constructed and arranged substantially as 40 and for the purpose described.

In testimony that I claim the foregoing as my own I affix my signature in presence of two witnesses.

JOHN J. McERLAIN.

Witnesses:

JAMES DU SHANE,
JEANIE ANDERSON.
